[57] **CLAIM**

The ornamental design for a hold down device for securing a line or flexible member to the ground, substantially as shown and described.

DESCRIPTION

FIG. 1 is a front elevation view of a hold down device for securing a line or flexible member to the ground incorporating the design of the present invention.

FIG. 2 is a side elevation view of the hold down device for securing a line or flexible member to the ground shown in FIG. 1.

FIG. 3 is a plan view of the hold down device for securing a line or flexible member to the ground shown in FIG. 1.
